Patented Dec. 5, 1916.

UNITED STATES PATENT OFFICE.

JACOB T. JOHNSON, OF ATLANTA, GEORGIA.

LIGHT-FIXTURE.

1,207,175.

Specification of Letters Patent.

Patented Dec. 5, 1916.

Application filed January 8, 1916. Serial No. 70,999.

To all whom it may concern:

Be it known that I, JACOB T. JOHNSON, a citizen of the United States, residing at Atlanta, in the county of Fulton and State 5 of Georgia, have invented a new and useful Light-Fixture, of which the following is a specification.

The present invention appertains to fixtures for gas burners, incandescent electric 10 lamps, or for other lights, and aims to provide a light fixture embodying a shade and holder provided with novel interengageable portions or means, whereby the shade can be readily applied to and detached from the 15 holder, and when applied will be effectively held or supported by the holder, the shade and holder each being simple, substantial and inexpensive in construction, and being devoid of set screws, clasps, and similar in- 20 dependent securing elements.

With the foregoing and other objects in view which will appear as the description proceeds, the invention resides in the combination and arrangement of parts and in 25 the details of construction hereinafter described and claimed, it being understood that changes in the precise embodiment of the invention herein disclosed can be made within the scope of what is claimed without 30 departing from the spirit of the invention.

The invention is illustrated in the accompanying drawing, wherein:—

Figure 1 is a perspective view of the shade and holder separated. Fig. 2 illustrates the 35 holder and shade in the act of being assembled or separated, the holder being shown in section and the shade in elevation. Fig. 3 is a bottom plan view of a modified form of holder. Fig. 4 is a view similar to 40 Fig. 1 illustrating a modification.

The holder embodies an annular gallery 1 having a spider 2 for attaching it to the body of the burner or lamp, as usual, the holder being stamped or otherwise formed 45 from sheet metal or other suitable material, and being suitably finished. The lower edge of the gallery 1 is provided with an inturned arcuate flange or lip 3 extending through approximately one-half a circle, or 180 degrees, and having its ends preferably rounded off. Opposite the relatively long flange 3, the lower edge of the gallery 1 is provided with an inturned rounded relatively narrow ear 4, preferably disposed midway between 50 the ends of the flange 3.

The shade 5 which may be of suitable

form and construction, being usually molded of glass, has at its upper end or neck an outturned annular flange 6 of suitable width and thickness in order that the flange is not 60 apt to be broken. This flange 6 is provided at one point only of its periphery with a notch 7 for the passage of the ear 4. At each side of the notch 7, the flange 6 is provided in its under or lower surface with a 65 radial groove 8 engageable with or adapted to receive the ear 4, and the grooves 8 are located a suitable distance from the notch 7 and need not be located far therefrom.

The holder and shade can each be inexpensively manufactured, and are strong and simple in construction.

In applying the shade to the holder, the shade is brought under the holder and tilted slightly, as seen in Fig. 2, and is then 70 moved transversely in the direction of the arrow to move one-half of the flange 6 over the flange or lip 3, in which event the shade can be swung to vertical position to bring the flange 6 completely within the gallery 75 1, the notch 7 during this operation being in registration with or below the ear 4 in order that said ear can pass through said notch when the shade is raised into place. Then, when the flange 6 is above the ear 80 4, the shade is turned slightly to let the flange 6 seat on the ear 4, and when the shade is turned in either direction, one of the grooves 8 will engage the ear 4 to limit the rotation of the shade, and to hold the 85 shade in place relative to the holder whereby the shade is not apt to be accidentally detached or rotated. The shade is thus effectively held in place, and the interengageable portions of the holder and shade are 90 substantial. The flange or lip 3 provides strong means to assist the ear 4 in supporting the shade, and it will be seen that the flange 6 of the shade need be provided with but a single notch 7, so that the 95 flange 6 is of greatest strength.

The present fixture can be used for gas, electric and other lights, and it is of course apparent that the holder and shade can be manufactured in various styles and sizes.

The holder illustrated in Fig. 3 comprises the annular gallery 1' and supporting spider 2', and the lower edge of the gallery 1' has a pair of inturned arcuate flanges or lips 3' which have their adjacent ends spaced 105 apart, and which have their remote ends terminating at the ends of an arc of 180 de-

grees, the same as the ends of the flange or lip 3. The ends of the flanges or lips 3' are preferably rounded off, and the lower edge of the holder 1' is provided diametrically opposite the space between the flanges 3' with an inturned ear 4', which is located midway between the remote ends of the flanges 3'. The shade is applied to this holder the same as with the first form of holder above described.

In Fig. 4, the holder comprises the annular gallery 1'' and spider 2'', and the gallery 1'' is provided with the arcuate flange or lip 3'' and the opposite inturned ear 4'', as in the form illustrated in Fig. 1, but in this case, the flange 3'' and ear 4'' are each corrugated, with the corrugations disposed radially of the gallery. The shade 5'' has the outturned annular flange 6'' provided at one point only with a notch 7'' for the passage of the ear 4'', and instead of using the grooves 8, the lower surface of the flange 6'' is provided with corrugations 8'' to engage the corrugations of the flange 3'' and ear 4'' when the shade is assembled with the holder. The corrugations 8'' may be arranged in series, and may extend completely around the flange 6'' with the exception of that point of the flange having the notch 7'', or the corrugations 8'' may be provided at certain points of the flange 6'' only, which ever is desired.

Having thus described the invention, what is claimed as new is:

35 1. A shade holder including an annular

gallery having a relatively long arcuate flange and an opposite relatively narrow ear, and a shade having an annular flange adapted to be shifted transversely onto the first mentioned flange, the shade flange having a single notch for the passage of said ear.

2. A holder including an annular gallery having an arcuate flange and an opposite ear, and a shade having an annular flange 45 adapted to be shifted transversely onto the first mentioned flange, the shade flange having a single notch for the passage of said ear, the shade flange having means at opposite sides of and adjacent its notch engageable with said ear for limiting the rotation of the shade relative to the holder.

15 3. A holder including an annular gallery having a relatively long arcuate portion and an opposite relatively narrow portion, and a shade having an annular flange adapted to be shifted transversely onto the first mentioned portion, the shade flange having a single notch for the passage of the second mentioned portion, said flange being corrugated, one of said portions being corrugated for the engagement of the corrugations of 50 said flange.

In testimony that I claim the foregoing as my own, I have hereto affixed my signature in the presence of two witnesses.

JACOB T. JOHNSON.

Witnesses:

IVY E. SIMPSON,
PHILOMENA A. ROCKELLI.
